SLICING MACHINE

Henry Fritz, Sr., Sheboygan, Wis., assignor of
one-half to Adam Hardt, Chicago, Ill.

Application July 27, 1931, Serial No. 553,282

21 Claims. (Cl. 146—153)

This invention relates to improvements in slicing machines, and refers more particularly to the mounting of the blades or knives in bread slicing machines.

5 In slicing machines of the class to which this invention belongs the loaves are conveyed past sets of moving blades or knives spaced apart a distance equal to the thickness of the desired slice. In many bakeries a single slicing machine 10 takes care of the entire sliced loaf output, and hence any break-down in the machine delays the entire output. The knives or blades are most susceptible to breakage, and in machines heretofore employed, the mounting of the knives or 15 blades has been such that even the replacement of a single broken blade necessitated a considerable delay.

It is, therefore, an object of this invention to 20 provide a novel and improved manner of mounting the blades of a slicing machine whereby any single blade may be detached and replaced without necessitating a delay of more than a few minutes.

It is also desirable to provide means for adapting 25 a single machine to different slice thicknesses, and heretofore changing of the slice thickness has required practically dismantling the entire knife mounting structure. It is, therefore, another object of this invention to provide means 30 whereby the knives are readily removable and insertable in sets so that any one set of blades or knives may be quickly withdrawn and another set inserted.

A further object of this invention is to generally 35 improve the design and construction of the blade mounting structure of slicing machines.

With the above and other objects in view which 40 will appear as the description proceeds, my invention resides in the novel construction, combination and arrangement of parts substantially as hereinafter described and more particularly defined by the appended claims, it being understood that such changes in the precise embodiment of the herein disclosed invention may be 45 made as come within the scope of the claims.

In the accompanying drawings, is illustrated 50 one complete example of the physical embodiment of this invention constructed according to the best mode so far devised for the practical application of the principles thereof, and in which:

Figure 1 is a transverse section through a slicing machine embodying this invention and illustrating the manner in which the loaves are conducted past the knives;

Figure 2 is a detail perspective view illustrating the manner of mounting the blades in sets;

Figure 3 is a cross sectional view taken through Fig. 1 on the plane of the line 3—3;

Figure 4 is a transverse sectional view taken through Fig. 3 on the plane of the line 4—4;

Figure 5 is an enlarged detail sectional view taken through Fig. 3 on the plane of the line 5—5;

Figure 6 is an enlarged detail view taken through Fig. 3 on the plane of the line 6—6; and

Figure 7 is a detail perspective view illustrating the manner of detachably mounting the individual blades.

Referring now more particularly to the accompanying drawings, in which like numerals indicate like parts throughout the several views, the numeral 5 represents a conveyer table along which loaves of bread "B" are conveyed in any suitable manner, guides 5' being provided to hold the loaves on the conveyer table. The loaves 20 are conveyed toward an inclined portion 6 in the table near the bottom of which is the slicing mechanism indicated generally by the numeral 7. The conveyer table may be supported in any suitable manner, not shown, and the slicing 25 mechanism is preferably supported from side rails 8 which may form part of the supporting structure of the conveyer. Extending across the bottom of the side rails 8 is a transverse support 9 upon which the slicing mechanism is directly 30 mounted.

The slicing mechanism comprises two transversely adjacent parallel sets of knives or blades 10 and 11 which are mounted for opposite vertical reciprocation by guide rods 12 and 12' respectively, having their lower ends secured to the transverse support 9 and their upper ends received in openings formed in a top cross piece 13, the outer ends of the cross piece 13 being attached to vertical side supports 14 extended 40 upwardly from the side rails 8.

Slidably mounted on the sets of guide rods 12 and 12' are substantially U shaped frames 15 comprising lower transverse rails 16 and side rails 17. These U shaped frames are preferably cast and have bored lugs 18 and 19 extended from the top and bottom respectively, of their side rails 17 to slidably receive the rods 12 and 12'. Opposite vertical reciprocation is imparted to the frames 15 by rocker arms 20 connected through pitmans 21 with the upper ends of the frames as at 22. The rocker arms 20 are fixed to the end portions of a cross shaft 23 and at a medial point the shaft has secured thereto, a lever 24 with which an actuating member 25 is

connected to oscillate the shaft 23 back and forth.

The inner edge portion of the side and bottom rails of the U shaped frames 15 are provided with continuous grooves 26 for the reception of plates 27. These plates are formed of stiff sheet metal and are rectangular in shape with a rectangular opening 28 of such size as to enable the loaves of bread "B" to pass therethrough. The top and bottom rails 29 and 30, respectively, of the plates are provided with means for readily detachably mounting sets of knives or blades 31. As seen in Fig. 3, the knives or blades carried by one plate are staggered with respect to the knives of the other, and the distance between the adjacent knives on each plate is equal to twice the thickness of the desired slice so that the distance between the adjacent knives, when assembled in the machine equals the slice thickness. The knives of both sets occupy the same transverse plane so that all of the knives engage the loaf at the same time with one set moving upwardly and the other downwardly. Hence there is no tendency for the loaf to turn or twist.

The specific manner in which the individual knives are attached to their carrying plates is best seen in Figs. 5, 6 and 7. It is observed that the bottom rails 30 of the knife carrying plates are provided with attaching blocks 32, the blocks of the two plates facing each other. The outer end portions of the blocks 32 are slotted to receive the lower ends of the blades 31, and bayonet slots 33 extending transversely across the blocks 32 are adapted to receive pins 34 fixed to the lower ends of the blades. The manner of attaching and removing the lower blade ends from the blocks 32 is obvious.

The upper ends of the knives are attached to the top rails 29 of the plates in a somewhat similar manner. Fixed to the top rails 29 and extending across the entire length thereof are angle plates 35. These plates form part of the means for attaching the upper ends of the blades and also stiffen the top rails 29.

The top rails 29 and the vertical flanges of the angle plates 35 are provided with rectangular openings 36 in line with each knife or blade, and slidably mounted in these apertures are attaching blocks 37. The attaching blocks 37 have grooves 38 in their opposite sides to receive the side edges 39 of the rectangular openings formed in the angle plate and thus slidably mount the blocks 37.

Like the attaching blocks 32 at the lower ends of the knives, the blocks 37 are slotted as at 40 for the reception of the upper end portions of the blades and have transverse bayonet slots 41 to receive their adjacent cross pins 34.

The blocks 37 are yieldably urged in an upward direction to maintain the blades 31 under tension, by expansive springs 42 coiled about screws 43 and confined between the heads of the screws and the horizontal flanges of the angle plates 35 through openings in which the screws extend to be threaded into tail pieces 44 on the blocks 37.

Each individual blade is thus readily detachably mounted from its carrying plate 30 and each plate as a whole is readily detachably mounted in its U shaped frame as best shown in Fig. 2. As hereinbefore stated, the side edge portions and the bottom edge portions of the plates are received in grooves 26 formed in the side and bottom rails respectively of the U shaped frames and to insert a plate carrying a set of knives, it

is only necessary to slide the same vertically into its frame. Screws 45 threaded in suitable openings in the frames and passing through openings in the plates are provided to hold the plates assembled with the frames. Hence to remove a plate and the knives carried thereby, it is only necessary to remove the screws 45 and lift the plate out of the frame, removal of the plates being facilitated by a handle 46 formed on the upper end of each plate. This mounting for the plates makes it possible to quickly adapt the machine to a different slice thickness, for plates may be kept on hand with the knives set at various distances apart and it is thus merely a question of inserting the proper set of plates.

Obviously, the plates must be provided in pairs inasmuch as the knives of one are staggered with respect to the other, and as the cutting edges of both sets of knives must face in the same direction.

At the point where the knives pass through the conveyer table, the table may be provided with a series of openings to accommodate the knives, but a more preferable construction is to provide a comb member 47 which forms a continuation of the conveyer table and provides a support for the loaves between the knives.

From the foregoing description taken in connection with the accompanying drawings, it will be readily apparent to one skilled in the art to which an invention of the character described appertains, that this invention affords a novel manner of mounting the knives of a slicing machine whereby the replacement of individual knives may be quickly effected, and whereby different sets of plates to accommodate different slice thicknesses may be quickly inserted and removed.

What I claim as my invention is:

1. In a bread slicing machine, a plurality of blades, means mounting the blades for reciprocation comprising, spaced reciprocable guides, a frame including spaced top and bottom members and side rails having a longitudinal sliding engagement with the spaced reciprocable guides, and means for connecting the opposite ends of the blades with the spaced top and bottom members of said frame.

2. In a bread slicing machine, a plurality of blades, means mounting the blades for reciprocation comprising, a reciprocable frame open at its top, a second frame including spaced top and bottom members, and side members, means slidably connecting the side members of the second frame with the first frame to enable the sliding of the second frame into and out of engagement with the first frame through the open top of the first frame, and means for connecting the opposite ends of the blades with the top and bottom members of the second frame.

3. In a bread slicing machine, a plurality of blades, means mounting the blades for reciprocation comprising, a substantially U shaped frame, means reciprocably mounting said frame, a second frame including spaced top and bottom members connected by side members, means providing a sliding connection between the side members of the frames whereby the second frame is slidably into and out of engagement with the first frame through the open top of the first frame, and means for connecting the opposite ends of the blades with the top and bottom members of the second frame.

4. In a bread slicing machine, a plurality of blades, means mounting the blades for recip-

5 rocation comprising, a substantially U shaped frame, means reciprocably mounting said frame, a second frame including spaced top and bottom members connected by side members, means providing a sliding connection between the side members of the frames whereby the second frame is 10 slideable into and out of engagement with the first frame through the open top of the first frame, and means readily detachably connecting the opposite ends of the blades with the top and bottom members of the second frame.

15 5. In a bread slicing machine, a plurality of blades, means mounting the blades for reciprocation comprising, a substantially U shaped frame, means reciprocably mounting said frame, a second frame including spaced top and bottom members connected by side members, means providing a sliding connection between the side members of the frames whereby the second frame is 20 slideable into and out of engagement with the first frame through the open top of the first frame, and readily detachable means individually connecting the opposite ends of each blade with the top and bottom members of the second frame.

25 6. In a slicing machine, a plurality of blades, means mounting the blades for reciprocation, comprising, a reciprocable carrier, a flat plate having its medial portion cut away to provide spaced top and bottom members connected by side members, means connecting the flat plate with the carrier, and means connecting the opposite ends of the blades with the top and bottom members of the flat plate comprising, a detachable fixed connection between one of said plate members and one end of the blades, blocks 30 slidably mounted from the other of said plate members, a detachable connection between the blocks and the opposite ends of the blades, and means for yieldably urging the blocks in a direction to impose tension on the blades.

35 7. In a bread slicing machine, a plurality of blades, means mounting the blades for reciprocation comprising, a substantially U shaped frame having spaced sides connected by a bottom member, the inner edges of the frame sides and bottom members having a continuous groove, means reciprocably mounting said frame, a plate having its side edges received in the grooves of the side members of the frame and its bottom edge received in the groove in the bottom member of the frame, said plate being slidable through the open top of the U shaped frame into and out of operative engagement therewith, means readily detachably securing the plate in its operative engagement with the frame, and means mounting the blades from the plate whereby the blades are removable from the frame as a unit.

40 8. In a slicing machine, a plurality of cutting blades, means mounting the blades for reciprocation comprising, spaced fixed supports, a substantially U shaped frame disposed between said supports and slidably mounted therefrom, a flat rectangular frame slidably engaged with the U shaped frame and removable therefrom through the open top of the U shaped frame, means to secure said rectangular frame in the U shaped frame, means connecting the opposite ends of the blades with the upper and lower members of the rectangular frame, and means connected with the U shaped frame to reciprocate the same.

45 9. In a slicing machine, a plurality of cutting blades, means mounting the blades for reciprocation comprising vertical fixed supports spaced from each other, a slotted member slidably mount-

5 ed on each vertical support, means connecting said slidably mounted members, means connected with one of said slidably mounted slotted members to reciprocate the same vertically, a substantially flat rectangular frame having its side edges engaged in the slots of the members slideable on the spaced supports, and means to connect the opposite ends of the blades with the upper and lower members of the flat rectangular frame.

10 10. In a slicing machine, a pair of spaced vertical fixed supports, grooved rails slidably mounted on each of said fixed supports with the grooves thereof in a common plane facing each other, means to connect said grooved rails at their bottoms to form a U shaped rigid frame, means connected with said rigid frame to reciprocate the same on the spaced fixed supports, a flat apertured plate slidably engaged in the grooves of the rails, said flat plate being readily detachable from the rigid U shaped frame by withdrawing the same upwardly through its open top, means to secure said flat apertured plate in the U shaped frame whereby the same reciprocates with the U shaped frame, and means to detachably mount a plurality of blades on said flat plate to extend vertically across the aperture in said plate.

15 11. In a slicing machine, two sets of reciprocable cutting blades, means to mount the blades with those of one set alternately positioned between those of the other set and with substantially equal spaces between the blades and all of their cutting edges in substantially a common plane, comprising a reciprocable frame for each 20 set of blades, said reciprocable frames each including connected side members having guideways facing each other, a rectangular blade carrying frame slidably engaged in the guideways of each reciprocable frame, means to readily detachably hold each of the rectangular frames in its respective reciprocable frame, blade supports 25 projected from the upper and lower cross bars of the rectangular frames, said blade supports of both rectangular frames having their end portions in substantially a common plane, so that the blades attached thereto have their cutting edges in substantially a common plane, and means connected with the reciprocable frames to simultaneously and oppositely reciprocate the sets of 30 blades.

35 12. In a slicing machine, two sets of reciprocable cutting blades, means to mount the blades with those of one set alternately positioned between those of the other set and with substantially equal spaces between the blades and all of their cutting edges facing one way, comprising a reciprocable frame for each set of blades, said reciprocable frames each including connected side members having guideways facing each other, an apertured flat metal plate slidably engaged in the guideways of each reciprocable frame, means to readily detachably hold the apertured flat metal plates in their respective reciprocable frames, said means enabling ready detachment of the plates from their frames, blade supports projected from the upper and lower cross pieces of the apertured plates with the blade supports of one plate facing those on the other and interposed alternately between those of the other, means to readily detachably connect the blades of one set to the supports of one plate and the blades of the other set to the supports of the other plate, and means connected with 40 45 50 55 60 65 70 75

the reciprocable frames to simultaneously and oppositely reciprocate the sets of blades.

13. In a bread slicing machine, two opposed reciprocable guides, a plurality of spaced cutting blades, means to mount the cutting blades from the two opposed reciprocable guides for ready detachment from the guides as a unit comprising, a flat relatively thin metal plate having its medial portion cut away to afford a substantially rectangular opening and providing upper and lower cross pieces connected by side members, the side members being readily detachably connectible with the reciprocable guides, blade supports carried by the upper and lower members, and means to readily detachably connect the ends of the blades to said supports.

14. In a bread slicing machine, a reciprocable frame having an open top, a plurality of cutting blades, means to mount the cutting blades from the reciprocable frame so as to be readily detachable therefrom by withdrawal through the open top of the frame as a unit, said means comprising an apertured flat metal plate, the aperture in said flat metal plate providing horizontally spaced members, fixed blade supports projecting from the face of one of said horizontally spaced members, movable blade supports projected from the face of the other horizontally spaced member, means to connect the ends of the blades with said blade supports, and yieldable means to urge the movable blade supports in a direction maintaining the blades taut.

15. In a bread slicing machine, a pair of spaced reciprocable units, means to simultaneously and oppositely reciprocate said units, a set of cutting blades for each reciprocable unit, and means to mount the sets of cutting blades one from each reciprocable unit so as to enable ready removal of the sets of cutting blades from the units without dismantling any portion of the reciprocable units whereby the substitution of one set of cutting blades for another is readily accomplished, said means comprising flat plate members apertured to afford horizontal spaced supporting rails, blade supports carried by said horizontally spaced supporting rails of each plate member, the blade supports of one plate member being disposed alternately between the blade supports of the other, and means to readily detachably connect the individual blades with the blade supports with all of the blades having their cutting edges facing one way.

16. In a slicing machine, a plurality of cutting blades, means mounting the blades for reciprocation comprising vertical fixed supports spaced from each other, a slotted member slidably carried by each vertical support, means connected with said slidably mounted slotted members to reciprocate the same vertically, a substantially flat rectangular frame having its side edges engaged in the slots of said slidably mounted members, and means to connect the opposite ends of the blades with the upper and lower portions of the flat rectangular frame.

17. In a slicing machine, a plurality of cutting blades, means mounting the blades for reciprocation comprising, vertical fixed supports spaced from each other, a slotted member slidably carried by each vertical support, means connecting said slidably mounted members, means connected with the structure formed by the slidably mounted slotted members and their connection to reciprocate the same vertically, a substantially flat rectangular frame having its side edges engaged in the slots of said slidably mounted mem-

bers, and means to connect the opposite ends of the blades with the upper and lower members of the flat rectangular frame.

18. In a slicing machine, two sets of reciprocable blades, means to mount the blades with those of one set alternately positioned between those of the other set and with substantially equal spaces between the blades and with all their cutting edges facing one way comprising, a reciprocable frame for each set of blades, said reciprocable frames each including connected side members having guideways facing each other, a rectangular blade carrying frame slidably engaged in the guideways of each reciprocable frame, means to readily detachably hold each of the rectangular frames in its respective reciprocable frame, blade supports projecting from upper and lower cross bars of the rectangular frames, and means connected with the reciprocable frames to simultaneously and oppositely 20 reciprocate the sets of blades.

19. In a slicing machine, two sets of cutting blades arranged with the blades of one set interposed between the blades of the other set and with the cutting edges of all of the blades facing one way, means to mount said sets of blades for simultaneous and opposite reciprocation and for bodily removal from the machine as complete units comprising, rigid side supports, a blade supporting frame for each set of blades having top and bottom members connected by side rails, blade supports projecting from the top and bottom members of said frames and to which the ends of the individual blades are attached, said blade supports being arranged so that those of one frame pass those of the other, and guide means to slidably connect the side rails of the blade supporting frames with said rigid side supports, said blade supporting frames being slidably disengagable from the guide means to enable withdrawal 40 of either blade supporting frame from the machine with all of the blades thereon.

20. In a slicing machine, a pair of spaced side frame members having upstanding portions, a pair of reciprocable blade frames, each having spaced cutting blades disposed between those of the other, means carried by said upstanding portions for guiding said blade frames during reciprocation, said blade frames being interchangeable with each other, means for reciprocating each of said blade frames in a direction opposite to the other, and detachable means connecting said blade frames with said reciprocating means, the space above said guiding means and blade frames being open and unobstructed whereby upon disengagement of said detachable means said blade frames may be bodily lifted from between said upstanding portions without disassembling the remainder of said machine.

21. In a slicing machine, a pair of spaced side frame members, a pair of reciprocable blade frames, each having spaced cutting blades disposed between those of the other, means carried by said side frame members for guiding said blade frames during reciprocation, means for reciprocating each of said blade frames in a direction opposite to the other, and detachable means connecting said blade frames with said reciprocating means, the space above said guiding means and blade frames being open and unobstructed whereby upon disengagement of said detachable means said blade frames may be bodily lifted from between said side frame members without disassembling the remainder of said machine.
